(57) **CLAIM**

We claim the ornamental design for a sample deck for selecting a covering for an architectural opening, as shown and described.

DESCRIPTION

FIG. 1 is a front isometric view of a sample deck for selecting a covering for an architectural opening showing our new design.

FIG. 2 is a front elevation view of the sample deck of FIG. 1.

FIG. 3 is a rear elevation view of the sample deck of FIG. 1.

FIG. 4 is a bottom plan view of the sample deck of FIG. 1.

FIG. 5 is a top plan view of the sample deck of FIG. 1.

FIG. 6 is a right side elevation view of the sample deck of FIG. 1; and,

FIG. 7 is a left side elevation view of the sample deck of FIG. 1.

The broken line showings of FIGS. 1-7 illustrate portions of a sample deck for selecting a covering for an architectural opening that form no part of the claimed design.
